UNITED STATES PATENT OFFICE.

CHARLES HERRMAN, OF NEW YORK, N. Y., ASSIGNOR TO UNDERWOOD TYPEWRITER COMPANY, OF NEW YORK, N. Y., A CORPORATION OF DELAWARE.

SYSTEM OF TYPEWRITER NOTATION.

Application filed April 26, 1919, Serial No. 292,962. Renewed August 7, 1922. Serial No. 580,310.

To all whom it may concern:

Be it known that I, CHARLES HERRMAN, a citizen of the United States, residing at New York city, in the county of New York and State of New York, have invented certain new and useful Improvements in Systems of Typewriter Notation; and I do hereby declare the following to be a full, clear, and exact description of the invention, such as will enable others skilled in the art to which it appertains to make and use the same.

In typewriting it is often desirable to be able to print a signature, trade mark or other characteristic depictive matter within the text itself or at any other point of the work sheet. This cannot be done at all; or only ineffectively, without individuality, by the use of the standard, selectively-interchangeable, language-writing alphabetic means of the typewriting machines now in use or known. It is an object of this invention to provide in a typewriter,—in addition to the usual, language-writing, constructive alphabetic type,—reproductive printing faces suitably corresponding in dimension to the spacing movement of the typewriter carriage and platen; such printing faces carrying fragments of the entire reproduction which is to be typed. By so, concretely and fully, embodying,—as by means of its fragmentary, selective and non-interchangeable, reproductive equivalents,—the signature, trade mark or design, as an entirety, in the type font, this method enables the typewriting of reproductive work in addition to the heretofore had constructive work.

The individual printing faces of the special additional reproductive group of type faces will contain the selective, non-interchangeable fragments of the entire reproduction; the divisions between the printing faces being made irrespective of the letters or other natural or ordinary divisions appearing upon the characteristic design as an entirety. Obviously, these type-dimension fragments when combined, by the successive striking of the keys of the typewriter in one fixed sequence, will reproduce the given facsimile signature, trade mark or design substantially without spaces indicating the impress of the individual type faces.

In the drawings:

Figure 1 represents a trade mark reproduction which may appear upon a single line of typewriting together with the individual prints from such faces for reproducing the trade mark in its entirety;

Figure 2 is illustrative of a two-line width trade mark and the formative equivalents thereof;

Figure 3 illustrates a three-line width trade mark design and the three formative groups thereof;

Figure 4 is illustrative of a trade mark, with registry notice appearing thereon, exemplifying the use of the invention where more than one line of letters appears upon the reproduction as an entirety; also the actual negative printing faces, as they will appear, as distinguished from the printing from such individual blocks as shown on the other figures;

Figure 5 illustrates a facsimile signature, together with the individual coordinated reproductive elements thereof;

Figure 6 is a perspective of a standard typewriting machine embodying the invention;

Figure 7 is a plan view of a key arrangement adapted to be used in practising the invention.

The size of the printing faces and impressions therefrom shown in the drawings, is somewhat enlarged to more clearly illustrate the invention. In actual usage the size will conform to the specific practical need.

In Figure 1, a trade mark reproduction is shown which will be printed upon a single line. The typewriter will be provided with an auxiliary set of keys, mechanically connected with the type bearing the essential printing surfaces, so that when successively struck in the usual manner, they will reproduce the trade mark as by the suitable correlation of the elements 110.

As clearly shown by Figures 2 and 3 illustrative of typing reproductions of a plurality of line spaces in vertical extent, the printing faces of the type will be suitably proportioned to properly correspond to the line-space rotary or other advancing movement of the platen, as well as to the letter spacing.

In Figure 4, 117 represents the trade mark; at 118, the individual positive fragments which conjointly go to make up the

reproduction; at 119, a presentation in facsimile of the actual, reproductive type faces. As is well known type-faces are, on their face-showing, as one looks at them, ⁵ exactly negative to the face showing of the reproduced or typewritten matter. It has been deemed needless to give more than one example of this art-corollary in this invention.

¹⁰ In Figure 5 attention is directed to the component type elements, 121, of the signature 120. The reproductive type, individually, are non-alphabetic and non-interchangeable; they conform to no recognized ¹⁵ standard, the divisions being made wholly irrespective of the position of the letters upon the printing faces.

In many typewriters each individual type bar carries two distinctly separate characters on its printing face,—mostly, a small letter of the alphabet and its capital are so associated. At normal position of the carriage or type basket, as the case may be, in differing machines, the small letters are ²⁵ typed; to get capitals and other, so called, upper case characters, a shift key is depressed. For the continuous impress of upper case characters the shift key is depressed and a shift-lock is thrown into engagement. The ready application of the above to this reproductive method is self evident. This method may, however, avail itself of the entire face area of the type as, ³⁰ for instance, in larger sized reproductions. ³⁵ Or it may combine the enlarged single-character type-face and the double-character type-face in the cooperative and coordinated reproduction of the predetermined characteristic design.

⁴⁰ In the use of the enlarged single-type face a slight curvature of the printing faces may be required to conform to the curvature of the paper upon the platen when the usual curved platen is used and a relatively wider inking ribbon may be used, whereby the proper impression will be produced upon the work sheet.

In the use of the method, it is intended that, as shown in Figure 6 at 122, at some ⁵⁰ convenient place upon the machine the particular reproduction embodied in the type-font will be identifyingly displayed. And, as shown at 123, an indexed chart indicative of the sequence of key operation essential to proper reproduction will also be instructively depicted.

Taking Figure 2 as example, both the ⁵⁵ entirety and its make-up are shown in Figure 6. A system of numbering the special reproductive keys is shown in Figures 2, 6, and the top row keys of Figure 7. To type this double-line-width trade mark, the lower case group, 111, of fragments 1, 2, 3, 4 and 5 are first impressed; the space bar is then ⁶⁰ struck once, as indicated by the instructive

numeral 6 thereon; and the line is completed by the group 112 of fragments 7 and 8. The platen is then advanced one line. The space bar is actuated as directed by the numeral 9 thereon; the shift key is pressed, the shift-lock is engaged, and thereby the upper case group 113 of fragments charted as 10, 11, 12, 13, 14, 15, 16 and 17 are impressed to complete the design. In Figure 2, S' indicates letter spaces, and the encircled numerals 6, 9, to the right of the chart, (Figures 2 and 7), indicate the sequence in which the space bar is to be operated to secure proper sequence of spacing.

In the preparation of the printing elements a design engraved or otherwise impressed upon a master block may be transferred to a group of individual printing blocks or elements of dimensions suitably corresponding to the letter and line spacing movements of the typewriting machine, the faces of said elements being flush with each other; or there may be collocated with their faces flush with each other a suitable number of blocks, each of a size adapted to service as type block or element, and the design may be engraved, etched, or otherwise impressed upon the surface of such collocated blocks, as may be found desirable. These printing blocks, or equivalents thereof, will ⁸⁵ then be suitably mounted individually upon the usual type bars of type-bar typewriters or otherwise suitably associated with the impact mechanism of the type-wheel or type-segment variety of typewriting machine. ⁹⁰

Application of this invention to three-character type faces, such as, say, on the Oliver #9 or Woodstock #5, or to type-wheel or type segment machines, while it varies in detail, does not depart from the ⁹⁵ spirit and scope of this invention.

Having described my invention in such manner as to enable those skilled in the art to which it appertains to make and use the same, what I claim and desire to secure by Letters Patent is:

1. In a typewriting machine adapted to write a language, punctuation marks, numerals and conventional symbols, as additional thereto and cooperative therewith, ¹¹⁵ means for reproducing a fixed, predetermined, individuality identifying symbol, comprising selectively operable type-faces carrying the suitably apportioned, fragmentary equivalents of the said symbol. ¹²⁰

2. In a typewriting machine adapted to write a language, punctuation marks, numerals and conventional symbols, as additional thereto and cooperative therewith, ¹²⁵ means for reproducing a fixed, predetermined, individuality identifying symbol, comprising selectively operable type-faces carrying the suitably apportioned, fragmentary equivalents thereof; the respective fragments bearing characteristics of the ¹³⁰

- symbol irrespective of the conformance of the letters, or other marks appearing upon the symbol, to the respective fragment-printing face width.
5. In combination with the usual font of selective types in a typewriting machine, a series of special selective, reproductive printing elements, each adapted to reproduce a fragment of a characteristic design, 10 said fragment being of surface dimensions corresponding, respectively, to a spacing movement of the typewriter, whereby, when the several special reproductive printing elements are selectively operated in proper sequence, a complete design may be reproduced upon the work sheet.
4. In combination with the usual font of selective types in a typewriting machine, a series of special, selective, reproductive 20 printing elements, each adapted to reproduce a fragment of a characteristic design, said fragment being of surface dimension corresponding to a letter spacing movement of the typewriter whereby when the several special reproductive printing elements are selectively operated in proper sequence, a complete design may be reproduced upon the work sheet.
5. In combination with the usual font of 30 selective types in a typewriting machine, a set of numerous special, selective, reproductive printing elements, each adapted to reproduce a fragment of a characteristic design, said fragment being of surface dimension corresponding to a spacing movement of the typewriter.
6. In combination with the usual font of 35 selective types in a typewriting machine, a series of special, selective, reproductive printing elements each adapted to reproduce a fragment of a characteristic design, said fragment being of surface dimensions corresponding respectively to the letter and line spacing movements of the typewriter, whereby when the several special reproductive printing elements are selectively operated in proper sequence, a complete, substantially unbroken design may be reproduced upon a work sheet.
7. In a typewriting machine having the usual selectively operated alphabet, numeral and conventional symbol printing elements, a series of selective special printing elements each bearing a fragment of a design or arbitrary symbol; a pattern design in 50 fragments on the machine frame each fragment corresponding with the fragment adapted to be printed by one of the special printing elements, identifying marks indicative of the order in which the fragments of the design are to be printed, the operative means for the special printing elements bearing identifying marks corresponding with the identifying marks of the fragmentary pattern-design.
8. In a letter-spacing typewriting machine, two sets of co-operative fragmentary types for reproducing a characteristic design, each set comprising successively operable type-faces carrying suitably apportioned arbitrary fragmentary equivalents of said design, one set for typing the upper part of the unitary design and the other set for typing the lower part of the unitary design under said upper part; means being 70 provided for affording a relative movement between the work-sheet and types to enable the lower set of types to co-operate with the upper set of types, so that the fragmentary impressions typed by the lower set 75 may be combined with the fragmentary impressions typed by the upper set, to complete the unitary design upon the work-sheet.

In testimony whereof I affix my signature.
CHARLES HERRMAN.
